ELECTROMAGNET

Osborne I. Price, Frederick, Md.

Application May 11, 1945, Serial No. 593,116

8 Claims. (Cl. 175—21)

1

My invention relates broadly to electromagnetic devices and more particularly to a coil end and terminal structure for electromagnetic devices.

One of the objects of my invention is to provide a simplified construction of terminal for electromagnetic devices which may be manufactured inexpensively on a mass production scale.

Another object of my invention is to provide a construction of electric terminal for electromagnetic devices in which the electric terminal may be readily molded with the coil end flanges of the electromagnetic device for establishing electrical connections between the opposite ends of the coil winding and an external circuit.

Still another object of my invention is to provide coil end structure for electromagnetic devices in which molded end flanges coat with metallic end plates for confining an electromagnetic winding in position with respect to a core structure where the material of the end flange have the property of forming a homogeneous protective enclosure about the coil winding with a chemical coating applied over the winding and end flanges.

Still another object of my invention is to provide a construction of plastic end flange for the core structure of an electromagnetic device having means for preventing warpage of the flange structure and at the same time being capable of uniting with a coating material for forming a substantially homogeneous enclosure for the electromagnetic winding on the core structure.

Still another object of my invention is to provide a construction of end flange for electromagnetic devices having terminals for the coil structure embedded in the flange which terminal consists of a pair of lugs, one pair of lugs constituting terminative means for the ends of the coil and the other pair of lugs constituting terminal posts for external connection of the coil in an external circuit.

Other and further objects of my invention reside in a construction of end flange and terminal arrangement for electromagnetic coils as set forth more fully in the specification hereinafter following by reference to the accompanying drawings in which:

Figure 1 is a side elevational view of an electromagnetic device with parts broken away and shown in section and illustrating in side elevation the end flange for the coil winding and embedded terminal arrangement associated therewith; Fig. 2 is an end view of the electromagnetic device illustrated in Fig. 1 and illustrating in end view the flange and terminal arrangement thereof; Fig. 3 is a fragmentary top plan view

of the device illustrated in Figs. 1 and 2 with parts broken away and shown in section; Fig. 4 is a longitudinal sectional view taken on line 4—4 of Fig. 3; Fig. 5 is a transverse sectional view taken on line 5—5 of Fig. 1; Fig. 6 is a transverse sectional view taken through the plastic end flange of the coil structure substantially on line 6—6 of Fig. 4 and showing in end elevation the embedded terminals molded within the end flange; Fig. 7 is a side elevational view of a magnetic core assembly with end flanges embodying the structure of my invention associated therewith; Fig. 8 is an end view of the assembly illustrated in Fig. 7 looking in the direction of arrow A and Fig. 9 is an end view of the structure shown in Fig. 7 looking in the direction of arrow B.

Referring to the drawings in more detail reference character 1 designates the magnetic frame structure of an electromagnetic device embodying the structural features of my invention, the magnetic frame structure having an angularly disposed portion 1a and a slotted end portion 1b for receiving the movable armature 16. The magnetic frame structure 1 provides a supporting means for the magnetic core 2 which is secured with respect to the angularly disposed portion 1a of magnetic frame 1 by means of the fastening screw 3 which engages the screw threads 2a in the end of core 2. The core 2 has a sleeve of insulation material 2b extending thereover between the end flanges of insulation material represented at 5 and 11. Flanges 5 and 11 are formed from any suitable plastic such as cellulose acetate or other plastic composition. The end flange 5 formed of plastic material is backed by a metallic flange 4, the two flanges being secured together as a unit by means of sets of suitable bonding members 6 and 7. The bonding members 6 and 7 may be rivets or pins or extensions from the end of core 2. Flange 5 of insulation material is precluded from buckling or warping by reason of the mechanical support continuously provided by the stiff metallic flange 4. The composite flange of insulation material 5 and metallic flange 4 provide mechanical support and insulation for the coil structure.

The magnetic core 2 has a transversely extending annular flange or head 8 thereon which serves as an abutment means for the end plate 9. The end plate 9 is centrally apertured to enable it to be passed over the core 2 from the end thereof which contains the screw threads 2a. The end plate 9 is curved along one edge thereof and has substantially parallel extending sides. The end plate 9 terminates at the end which is opposite

the curved end thereof in a plane extending transversely to the parallel sides of the end plate. The end plate 9 is slotted at 10 to avoid the establishment of a closed circuit path through the end plate adjacent the electromagnetic winding for preventing the setting up of undesirable eddy currents.

The end flange 11 formed from plastic material has the face thereof recessed at 11a in a contour which conforms with the shape of the curved end of the end plate 9 for receiving the end plate 9 for thus reinforcing the plastic end flange and preventing warpage thereof.

The plastic end flange 11 has embedded therein the thin flat sheet-like terminal plates 12 and 14. The terminal plates 12 and 14 are arcuate in shape and extend for distances substantially less than a quadrant. The terminal plates 12 and 14 have eyelet lug connectors 12a and 14a at one extremity thereof and lug connectors 12b and 14b at the opposite ends thereof respectively. The eyelet lug connectors 12a and 14a serve as terminals for the opposite ends of the coil of the electromagnetic winding 15 while the lug terminals 12b and 14b serve as terminal means for establishing connection with an external electrical circuit. The terminal plates 12 and 14 are apertured at spaced intervals as represented at 12c and 14c allowing the passage of the plastic material of the end plate 11 therethrough for firmly anchoring terminal plates 12 and 14 in embedded position within the plastic end flange 11.

The electromagnetic system as thus described is associated with the frame support 1 through fastening screw 3 and is aligned with the rockable armature 16. The armature 16 has longitudinally extending actuating arms 16a and 16b thereon for operating spring pile-up assemblies supported by the magnetic frame 1. Lugs 17 are provided on an extension of the armature 16 and serve as supporting means for the armature with respect to the projections 1b of the magnetic frame 1. The armature 16 is maintained under tension by means of flat spring 18 which exerts continuous tension against the edge of the armature 16. The flat spring 18 is secured in position by plate 19 and securing screws 20 fastened to the frame 1. A spring pile-up assembly is represented generally at 21 arranged for operation by arm 16b of the armature 16. A second spring pile-up assembly may be supported on the frame 1 for activation by the arm 16a of the armature 16.

The method of reinforcing the plastic end plates 5 and 11 of the electromagnetic system by stiff metallic members and the method of embedding the terminals in the material of the plastic end plate 11 has proved to be very effective in manufacture, production and use. I realize that modification may be made in detail in the structure of my invention and I desire that it be understood that I intend no limitations upon my invention other than may be imposed by the scope of the appended claims.

What I claim and desire to secure by Letters Patent of the United States is as follows:

1. A terminal structure for electromagnets comprising in combination a core structure, an end plate of plastic material on said core structure, arcuate shaped terminal members embedded in said end plate, projections formed on said arcuate shaped terminal members, a winding carried by said core structure, connections from the opposite ends of said winding to an individual one of the projections on said terminal members and terminal lugs formed on the other projections on

said terminal members and constituting binding posts for connection through an external electrical circuit.

2. A coil structure comprising a magnetic frame, a core structure supported by said frame, a metallic end flange associated with opposite ends of said core structure, one of said metallic end flanges having the plane of its surface extending in surface contact with the surface of

10 said magnetic frame and the other of said metallic end flanges having one edge thereof extending in surface contact with said magnetic frame structure, coil end flanges of insulation material associated with said core structure and 15 abutting against said metallic end flanges and reinforced thereby for preventing warpage thereof and a coil winding carried by said core intermediate said coil end flanges of insulation material.

20 3. A coil structure comprising a magnetic frame, a core structure supported by said frame, a metallic end flange associated with opposite ends of said core structure, one of said metallic end flanges having the plane of its surface ex-

25 tending in surface contact with the surface of said magnetic frame and the other of said metallic end flanges having one edge thereof extending in surface contact with said magnetic frame structure, coil end flanges of insulation material

30 associated with said core structure and abutting against said metallic end flanges and reinforced thereby for preventing warpage thereof, a coil winding carried by said core intermediate said coil end flanges of insulation material and terminal members embedded in one of said coil 35 end flanges of insulation material and electrically connected with the opposite end of said coil winding.

4. A coil structure comprising a magnetic frame, a core structure supported by said frame, a metallic end flange associated with opposite ends of said core structure, one of said metallic end flanges having the plane of its surface ex-

45 tending in surface contact with the surface of said magnetic frame and the other of said metallic end flanges having one edge thereof extending in surface contact with said magnetic frame structure, coil end flanges of insulation material associated with said core structure and abut-

50 ting against said metallic end flanges and reinforced thereby for preventing warpage thereof, and a coil winding carried by said core intermediate said coil end flanges of insulation material, one of said metallic end flanges being 55 radially slotted for avoiding the establishment of a closed circuit path adjacent said winding.

5. A coil structure comprising a magnetic frame, a core structure supported by said frame, a metallic end flange associated with opposite ends of said core structure, one of said metallic end flanges having the plane of its surface ex-

60 tending in surface contact with the surface of said magnetic frame and the other of said metallic end flanges having one edge thereof extending in surface contact with said magnetic frame structure, coil end flanges of insulation material

65 associated with said core structure and abutting against said metallic end flanges and reinforced thereby for preventing warpage thereof, the metallic end flange which has its edge extending in surface contact with said frame being 70 radially slotted from said core to said frame for avoiding the establishment of a closed circuit path adjacent said coil winding.

75 6. A terminal structure for electro-magnets

comprising in combination with a magnetic core structure, end plates of metallic material associated therewith, end plates of plastic material extending adjacent said end plates of metallic material, one of said plastic end plates having arcuate shaped terminal members embedded therein in position spaced from said magnetic core structure, terminal lugs on one end of each of said arcuate shaped terminal members and connecting means formed on the opposite ends of each of said arcuate shaped terminal members and means for maintaining said arcuate shaped terminal members in embedded relation to said plastic end plates.

7. A terminal structure for electro-magnets comprising in combination with a core structure, an end plate of plastic material on said core structure, flat sheet-like arcuate shaped terminal members embedded edgewise of said plastic end plate, terminal lugs formed on one end of each of said terminal members and connection means formed on the opposite ends of each of said terminal members and a coil winding carried by said core structure and electrically connected with said connecting means.

8. A terminal structure for electro-magnets comprising in combination a core structure, an end plate of plastic material on said core structure, flat sheet-like arcuate shaped terminal

members embedded in said plastic end plate in spaced relation to said core structure, said terminal members each having apertures formed therein for the passage of the plastic material of said plate therethrough for establishing interlocking relation between said terminal members and said end plate, a lug formed on one end of each of said terminal members and connecting eyelets formed on the opposite end of each of said terminal members, and a coil winding carried by said core structure and electrically connected with said connecting eyelets for forming a circuit path to the said lugs.
